SELF-OPENING CLOSURE

Nathaniel B. Wales, New York, N. Y., assignor
to Industrial Patent Corporation, New York,
N. Y.

Application March 31, 1947, Serial No. 738,296

5 Claims. (Cl. 220—47)

1

This invention relates to self-opening containers, or what is commercially known as tin cans, and is an improvement and a continuation in part of my pending United States Patent application Serial Number 578,451, now Patent No. 2,449,186.

Whereas in the above mentioned patent application I employ a collapsed chamber in which I insert a gas generating substance which generates a pressure when subjected to heat, exterior to the actual double folded seam which forms the hermetical seal between the container and the top or closure of the container, I now insert a gas generating substance, which in this case has explosive or rapid burning characteristics within the double folded seam which now constitutes the collapsed chamber.

In this manner advantage is taken of the conventional production technique and machine equipment as is now in use in can manufacturing to carry out the basic theme of my invention, which is the inflation of a collapsed chamber to release the closure from the container.

It is, moreover, conventional to insert within the inner fold of the double folded interlocking seam as above described a fluid rubber compound to insure the hermetical seal essential between the closure and the container. I therefore may add to this rubber compound a relatively low ignition temperature explosive or an explosive compound having viscous characteristics may be used alone.

In close proximity to the double folded interlocking seam securing the closure to the container I form a circumferential scored section on either the container or the closure so that by the inflation of the collapsed chamber in the seam by the pressure wave generated therein the scored section of metal will sever and release the closure from the container.

This objective may be accomplished in several modifications of structure which are disclosed herewith.

Other objects and details will be more specifically described in the following specifications and drawings in which:

Figure 1 is a side view in elevation of a container embodying the invention, the upper portion of which is shown in section.

Figure 2 is an enlargement of the double seam as shown in Figure 1 taken on line A—A.

Figure 3 is the same section as shown in Figure 2 as it would appear after it has undergone inflation due to the ignition of the gas generating sub-

stance incorporated within the double folded seam during fabrication.

Figure 4 is an enlarged section similar to Figure 2 except that it shows a modification of the anvil or stiffened section of the body of the container in close proximity to the scored ring in the body of the container.

Figure 5 is an enlarged view in section taken on line A—A in Figure 1 of a modification of the disposition of the double folded interlocking seam between the closure and the container, also a modification of the position of the circumferential scored ring in respect to the seam.

Figure 6 is the same enlarged view as is seen in Figure 5 but indicating the position of the seam after being dilated by the ignition of the explosive substance incorporated therein.

Referring more specifically to the drawings similar numerals refer to similar parts:

20 Numeral 1 is the body of the container, 2 is the closure which is conventionally secured to the container body by the double folded seam 3.

Considering the double folded seam 3: the top end of the container body 1 appears in the double fold at 4 whereas the inner fold 5 of the metal of the closure 2 is wrapped around member 4 in such a manner as to leave a circumferential cavity 6 therebetween. This cavity 6 contains the explosive or gas generating substance 13, which is so compounded and proportioned that when it is ignited by the application of heat, as from a match 7, the ensuing pressure generated dilates the cavity 6 as seen in Figure 3.

It is to be noted that as cavity 6 is inflated the fold 5 in expanding inwardly presses against the contacting face of the container wall section 8 assisting in the pressure seal therebetween and forcing the wall of the container inwardly as seen in Figure 3. However in distorting the metal of this section of the container inwardly at a typical segment of the container 1 as enumerated at 9 the circumferentially scored ring 10 ruptures and the closure 2 together with the inflated double folded seam 3 are separated from container 1.

In order to focus the inward thrust of the expanding seam 3 due to its contact with the wall of container 1 on to the scored ring 10 in container 1 a stiffened section 11 of the container 1, which may be produced by beading the metal, or the like, is positioned in close proximity to the scored section 10 in container 1. This beading acts as an anvil and focuses the distortion of the wall of the container 1 on to the weakened section of the container wall as defined by the scored ring 10.

In Figure 4 this stiffened section is shown at 12 made in the form of a band of metal forced into the body of the container during its fabrication. It is to be noted that the scored section 10 in the wall of container 1 is shown in Figure 4 as an external score in the wall of container 1 in contrast to the internal scoring as shown in Figures 2 and 3.

Referring to a modification of the positioning of the seam and the position of the scoring as is shown in Figures 5 and 6. The gas generating substance 13 may be stenciled or coated on the surface 14 of the closure 2 prior to the folding of the closure into the double folded seam 3, which is analogous to the application of the viscous rubber compound now used in can manufacture as previously described.

The annular scored ring section 15 is now positioned in the closure 2 at a point where it is subject to a high disruptive force which is a component of the inflation of the chamber 16. As the chamber 16 is formed by the pressure wave resulting from the ignition of substance 13 the sheet metal member 17 is drawn downward towards the expanding chamber 16 causing the closure 2 to rise due to the metal portion 18 slipping around the curvature 19 of seam 3, and this downward pressure further flexes the scored ring 15. In this manner by the combined tension and flexation which the scored section 15 undergoes it is severed and the closure 2 is released from the container.

A further force resultant tending to eject the severed closure 2 from the body of the container 1 resides in the fact that the explosive substance 13 is positioned substantially in the base of the seam 3 and the maximum distension of seam 3 would occur substantially as indicated. Therefore the wall 20 of the container opposite the seam 3 would exert an upward force component on the closure 2.

It is evident to those skilled in the art that the seam 3 might be positioned in a different plane, as for example, if the axis of the container of which only a fragment is shown in Figure 4 is the line B-B the double folded seam 3 instead of being in a plane parallel to the axis B-B, as is seen in Figure 5 might extend outwardly from the body of the container 1 and thus be at right angles to the line B-B.

The basic concept of this invention is the utilization of the conventional multi folded seam which forms a hermetical seal between the closure and the container as a collapsed chamber and by inserting a gas generating substance therein the resultant dilation of the seam is harnessed to sever the closure from the container. This concept results in a low cost embodiment of my invention since only a slight alteration of existing standard fabrication procedure in tin can manufacture is necessary to achieve the desired result.

What I desire to protect by United States Letters Patent is encompassed in the following claims:

1. An hermetical closure for a container adapted to be self-opened by the application of heat thereto comprising a seal composed of one perimeter of said container and the outer perimeter of said closure interlocked in a multi folded seam, a scored section formed in said container in close proximity to said multi-folded seam, a circumferential bead formed in the wall of said container below said scored section and adjacent thereto adapted to stiffen the wall of said container

against deformation, an explosive substance incorporated within said seam, the ignition of which inflates said seam thereby deforming the wall of said container above said bead to that extent sufficient to cause severance along said scored section.

2. An hermetical closure for a container adapted to be self-opened by the application of heat thereto comprising a seal composed of the upper perimeter of said container and the outer perimeter of said closure interlocked in a plural folded seam, an explosive substance incorporated within said seam, a circumferential scored section formed in said container in close proximity to said double folded seam, a circumferential bead formed in the wall of said container below said scored section and adjacent thereto in order to stiffen the wall of said container against deformation whereby on the inflation of said seam by the ignition of said explosive therein the wall of said container is deformed above said bead to that extent sufficient to cause severance along said scored section.

3. Hermetical sealing means for a container adapted to self-open by the application of heat thereto comprising a closure, a plural folded seam securing the periphery of said closure to one end of said container, a circumferential scored section formed in said container in close proximity to said seam, stiffening means incorporated in said container adjacent to and below said circumferential scored section, an ignitable gas generating substance positioned within one of the folds of said seam in order to inflate said seam when ignited by the application of heat thereto and by said inflation to sever said scored section in said container.

4. Hermetical sealing means for a container adapted to self-open by the application of heat thereto, comprising a closure, a plural folded seam securing the periphery of said closure to one end of said container, a circumferential scored section formed in said closure in close proximity to said seam, an ignitable gas generating substance positioned within one of the folds of said seam in order to inflate said seam when ignited by the application of heat thereto and by said inflation to sever said scored section in said closure.

5. Hermetical sealing means for a container adapted to self-open by the application of heat thereto, comprising a closure, a plural folded seam securing the periphery of said closure to one end of said container, a circumferential scored section formed in said closure in close proximity to and above said seam, an ignitable gas generating substance positioned within one of the folds of said seam in order to inflate said seam when ignited by the application of heat thereto and by said inflation to sever said scored section in said closure.
